UNITED STATES PATENT OFFICE.

SIMEON P. WATSON, OF BROOKLYN, NEW YORK.

BARBER'S INDICATOR.

SPECIFICATION forming part of Letters Patent No. 448,392, dated March 17, 1891.

Application filed June 7, 1890. Serial No. 354,664. (No model.)

To all whom it may concern:

Be it known that I, SIMEON P. WATSON, of Brooklyn, Kings county, and State of New York, have invented a certain new and useful Improvement in Barbers' Indicators, of which the following is a specification.

I will describe a barber's indicator embodying my improvement, and then point out the novel features in the claim.

10 In the accompanying drawings, Figure 1 is a front view of an indicator. Fig. 2 is a back view thereof and certain appurtenances.

Similar letters of reference designate corresponding parts in both the figures.

15 Referring to the drawings, A designates a dial, and B an index mounted upon a spindle C, protruding through the center of the dial and having rotary movement around the dial. The dial is intended to be marked consecutively with figures from the starting-point of the index. In the present instance the numeral "1" is at the top part and over the center of the dial, and the figures run to the right around the dial. On the spindle C a ratchet-wheel D is affixed in rear of the dial. The spindle may be supported in any suitable way to rotate—as, for instance, in a bracket d, fastened to the rear side of the front of the case.

20 D' designates a stop-pawl, which is pivotally connected to the case and precludes the rotation of the ratchet-wheel in the wrong direction.

D² designates a pawl pivotally connected at one end to a lever E and held in contact with the ratchet-wheel by a spring e, which is fastened to said lever. The lever E is fulcrumed between its ends to a bracket E', which is secured to the case of the instrument.

25 When this lever is vibrated in one direction, the pawl D² imparts a movement to the ratchet-wheel sufficiently great to effect a movement of the index B from opposite one figure of the dial to the next.

30 F designates a pawl rigidly connected to the lever E close to the pawl D² and in a position to coact with the ratchet-wheel. This pawl is longitudinally slotted, so that it may be adjusted to project more or less from the lever or to adjust it relatively to the movement of the lever as the parts become worn. The object of this pawl is to prevent the pawl

D² from moving the ratchet-wheel more than one tooth at a time, and to accomplish this purpose said pawl F is so arranged that after 55 the movement of the ratchet-wheel through one tooth under an impulse from the pawl D² the said pawl F will bear against the top of another ratchet-tooth and block the ratchet-wheel. The apparatus represented in Fig. 60 2 shows this coaction of the pawls D² and F.

G designates an electro-magnet secured to the case of the instrument. Its armature g is affixed to the lever E above the fulcrum of the latter. Hence when this electro-magnet 65 is energized it will vibrate the lever in such direction as to effect a partial rotation of the ratchet-wheel.

The movement of the lever E may be limited by stops e' e². These are made in the 70 form of screws fitted to a bracket which is fastened to the case of the instrument, and when so made the stops will of course be adjustable.

Whenever the electro-magnet becomes de- 75 energized, the lever is retracted by means of a spring H, which at one end bears against a pin fastened to the lever below the fulcrum of said lever and at the other end is connected with the case of the instrument.

To the lower extremity of the lever I have shown the hammer I of a bell I' affixed. Hence when the lever is retracted this bell will be sounded.

The ends of the coils of the electro-magnet 85 G are connected to binding-posts J' J², which also have fastened in them circuit-wires K' K², communicating with a battery L and with push-buttons M' M². These push-buttons will be adjacent to the barbers' chairs. Normally the electric circuit will be open. Each 90 time a push-button is manipulated the circuit will be temporarily closed and will thereby cause the electro-magnet G to be energized and the index B to be moved from 95 one figure to the next on the dial. The push-buttons, being of the usual spring-actuated type, will open the circuit whenever released. When this happens, the electro-magnet will be de-energized and the bell I' will be struck. 100 It is the duty of each barber to touch his push-button M' or M² at the time of serving or attending to each customer. The index B will therefore indicate at any time the num-

ber of persons who have received attention in the course of the day, assuming that the index is returned to the starting position each day. As each person enters he may receive a numbered check of any desired construction. The first person who enters in the morning will receive check No. 1, and the index B will point to "1;" but at many times in the day the number of people who have received checks will be greater than the number of people waited upon, and the number on the check received by the last person will be higher than the number opposite the index—as, for instance, if a man entered the shop at a time when four people were already unattended to the number of his check would be five numbers above the number to which the index B would point.

It is possible from the use of this indicator with the checks for any person immediately on entering the shop to learn by comparing the number of his check with the number to which the index B points how many persons

are ahead of him awaiting attention. He can therefore, after having secured his turn, 25 go away, if he desires, and count on having his turn when he comes back. In this way time may be saved and confusion frequently obviated.

What I claim as my invention, and desire 30 to secure by Letters Patent, is—

The combination, with an electro-magnet and circuit-changers, of a ratchet-wheel, an oscillating lever, stops for limiting the movement of the lever, a pawl pivoted to said lever and 35 operating to move the ratchet-wheel when the lever is attracted by the electro-magnet, and a pawl adjustable on and rigidly secured to the lever, the said rigid pawl being adapted to engage the upper portion of a tooth below 40 the pivoted pawl to block the inertia of the ratchet-wheel, substantially as specified.

SIMEON P. WATSON.
